HENRY K. STACK, OF PORTLAND, OREGON

CONSTRUCTION IN WATER CRAFT

Application filed October 24, 1929. Serial No. 402,175.

The primary purpose and object of my device is to provide a boat of greatest ability and one that may be propelled through the water in maximum speed commensurate with 5 the resistance offered to the passing of the same through the water.

The invention consists primarily of a plurality of uniformly shaped stream lined pontoons secured together in spaced relationship 10 and depending from the body element of the boat so that the body element of the boat is primarily intended to ride entirely above the normal surface of the water through which the boat is being propelled by power means.

15 The pontoons will be normally held submerged in rough weather as the boat is propelled through the water, thereby stabilizing the boat and rendering it substantially undisturbed by the roughened surface of the 20 water over which the same is being propelled. The propeller being disposed central of the pontoon assembly insures its full efficiency in rough weather because of the fact that it will be submerged at all times.

25 One of the objects of my invention is to provide a boat structure that will offer a minimum of propulsion resistance at relatively high speeds.

A further object of my invention consists 30 in providing a construction that will insure full efficiency from the power being supplied for propelling the same, due to the fact that the propeller will be submerged to the full 35 wheel depth at all times, and further due to the stream line shape of the pontoons.

A further object of my invention resides in a structure that will offer minimum resistance to its propulsion through the water, that will attain the maximum speed for the power of 40 propulsion used, that will be relatively stable in the roughest of weather and that will ride upon an even keel at all times.

A further object of my new and improved 45 device consists in providing a structure that may be turned with greatest freedom of movement, and within a minimum of turning radius.

50 With these and incidental objects in view, the invention consists in certain novel features of construction and combination of

parts, the essential elements of which are set forth in the appended claim, and a preferred form of embodiment of which is hereinafter shown with reference to the drawings which accompany and form a part of this specification. 55

In the drawings:

Fig. 1 is a side elevation of a relatively large boat shown assembled and in upright position in the water. 60

Fig. 2 is an end view of the mechanism illustrated in Fig. 1.

Fig. 3 is a sectional, plan view of the assembled device, the same being taken on line 3—3 65 of Fig. 1 looking in the direction indicated.

Fig. 4 is a side view of a modified form of construction, the same having a plurality of relatively small stream lined, submersible pontoons depending from a relatively large, multifaced pontoon above which the boat hull normally rides and superposed above the normal water line. 70

Fig. 5 is a cross sectional view, taken on line 5—5 of Fig. 4, looking in the direction indicated. 75

Fig. 6 is a longitudinal, sectional, side view of one of the pontoons illustrating the same in preferred embodiment.

Fig. 7 is a side elevation of a relatively small pleasure boat illustrating a plurality 80 of pontoons depending therefrom that are normally submerged.

Like reference characters refer to like parts throughout the several views.

I preferably form my boat of a plurality of 85 submersible pontoons 1, rigidly secured together by strut fastenings 2, the same being depended from the under side of the hull 3. Each of the pontoons is secured rigidly together by struts or by any other suitable fastening means and the pontoon assembly is secured to the under side of the hull by any suitable fastening means as by hollow webs or hollow struts 4. These large webs or struts are placed central of the pontoons and lighter struts 5 extend from the tips or ends of the pontoons to each other and to the hull. 90

An engine carrying hollow strut 4A is rigidly secured centrally of the underside of the hull and also secured centrally of and 95 100

to the centrally disposed pontoon, and adapted to maintain the prime mover for the ship. A propeller 10 extends outwardly from the engine carrying strut. Heretofore it has been the general custom to place the propeller at or near the stem of a vessel but I have found that more satisfactory results are obtained when the propeller is disposed slightly astern of the central portion of the ship as shown in Fig. 1. The stream line of the flow of the water through and between the pontoon develops a maximum power application to the direct propelling of the assembly through the water. The pontoons normally have sufficient buoyancy to maintain the hull entirely out of the water and the construction of the pontoons so as to have a plurality of faces, both top and bottom, that are substantially equal in area and adapted to being normally submerged, prevents rougher surface water from unduly agitating the hull which normally rides free and clear of the surface, thereby stabilizing the hull in relatively rough water. The major portion of the pontoons is normally maintained submerged with the broad surfaces of the pontoons being disposed at the top and bottom of the pontoons. Rough water striking the under surface of the boat hull will exert a lifting energy to the pontoons. The pontoons being relatively broad at their top and bottom surface offer a maximum resistance to an up and down movement being imparted to the hull and at the same time offer a minimum of resistance to the driving of the same through the water by power means.

I have found splendid results are obtained wherein the device is made as illustrated in Fig. 4, illustrating a relatively large pontoon disposed immediately below the hull 7 with a plurality of web struts disposed between the pontoon 6 and the hull 7. The hull 7 is superposed the pontoon 6 and a part of the upper surface of the pontoon is normally out of the water and not submerged entirely therein. A plurality of smaller pontoons 9 are disposed below the central pontoon 6.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claim which follows:

What I claim is:

A watercraft comprising a hull, a main pontoon disposed centrally under the hull, pairs of pontoons of smaller dimension disposed intermediate between the hull and the main pontoon, said pontoons being in different planes and arranged so that the greatest vertical resistance is centrally of the watercraft, an engine carrying strut disposed

immediately above the main pontoon and secured to the underside of the hull and adapted for, intercommunicating between the hull and the main pontoon, and a plurality of struts connecting the pontoons with each other and with the hull for maintaining the structure rigidly together.
